TETHERED BALL TOY

Alfred C. Kather, Los Angeles, Calif.

Application May 6, 1957, Serial No. 46,015

Term of patent 14 years

(Cl. D34—15)

Fig. 1 is a perspective view of a tethered ball toy, showing my new design, the rear having substantially the same appearance; and,

Fig. 2 is a side elevational horizontal view thereof, to a somewhat reduced scale, the opposite side having substantially the same appearance.

I claim:

The ornamental design for a tethered ball toy, as shown and described.
